UNITED STATES PATENT OFFICE.

JOHN M. UNDERWOOD, OF PARIS, ARKANSAS.

EXHAUST FOR INTERNAL-COMBUSTION ENGINES.

1,156,447.

Specification of Letters Patent.

Patented Oct. 12, 1915.

Application filed December 11, 1913. Serial No. 805,967.

To all whom it may concern:

Be it known that I, JOHN M. UNDERWOOD, a citizen of the United States, residing at Paris, in the county of Logan and State of Arkansas, have invented certain new and useful Improvements in Exhausts for Internal-Combustion Engines, of which the following is a specification.

My invention relates to improvements in internal combustion engines and more particularly to the exhaust thereof, being designed with a view to eliminating the liability of a return of the exhaust products, and at the same time relieving the vacuum which frequently obtains in the exhaust pipe and pocket of the engine immediately following the closing of the exhaust valve.

To these and other ends, the nature of which will be readily understood as the invention is hereinafter disclosed, said invention consists in the improved construction and combination of parts hereinafter fully described, illustrated in the accompanying drawings, and more particularly pointed out in the appended claim.

In the accompanying drawings, in which similar characters indicate similar parts, Figure 1 is a vertical sectional view taken through the attachment and the pipes leading to and from the attachment. Figs. 2 and 3 are sectional views taken on the lines 2—2 and 3—3 respectively of Fig. 1.

When the exhaust valve of an internal combustion engine closes at the end of the exhaust stroke, the pressure tending to drive the exhaust gases out of the exhaust pipe is of course suddenly cut off. During the movement immediately following the closing of the exhaust valve, however, the gases continue to rush through the exhaust pipe because of their inertia. Thus a partial vacuum is created at the inner end of the exhaust pipe (or exhaust pocket as it is sometimes called). In case the exhaust valve does not seat properly a small amount of the exhaust gases may be drawn back into the cylinder during the first part of the intake stroke.

The structure devised by me for overcoming this difficulty is shown in the accompanying drawings, consisting of a three-way casing 10 having one of its openings 11 adapted to be threaded to the exhaust outlet 12 of the cylinder, the other two openings 13 being substantially in vertical axial aline-

ment, and an enlarged portion 13 being threaded to the casing to form a continuation of the upper opening 14, while the lower portion of the casing is enlarged, as at 15, with the lower opening 16 threaded to receive a valve seat 17, to which, if desired, a pipe 18 may be secured. The enlargement 13 has its outer end threaded to receive the exhaust pipe 19.

In each of the enlarged portions 13 and 15 of the attachment, I mount valves 20 and 21, these being supported in suitable spiders 22. These valves are adapted to operate by gravity, the valve 20 being adapted to open when pressure is placed within the casing, 65 while the valve 21 is adapted to be opened under suction action within the casing. The valves are of a weight which will provide for maximum efficiency.

Regarding the operation of the attachment it will now be seen that during the exhaust stroke of the engine piston the burnt gases will be forced out under pressure and will escape through the valve 20 to the atmosphere through the pipe 19. At this time 75 the internal pressure in the casing 10 together with the action of gravity holds the air valve 21 closed. When the exhaust valve of the cylinder closes, however, the pressure tending to unseat the valve 20 and drive out 80 the exhaust gases will be cut off. The inertia 85 of the gases is sufficient to cause their continued passage through the valve 20 for a moment only. This continued passage of the gases after the closing of the exhaust valve of the cylinder results in the production 90 of a partial vacuum in the pipe 12. This vacuum is relieved by the present device since the valve 21 lifts under atmospheric pressure to admit sufficient fresh cool 95 air in the casing 10. It is now to be explained that the opening of the air valve 21 is accompanied by a closing of the exhaust valve 20. Thus the exhaust gases present 100 in the pipe 19 when the exhaust valve of the cylinder closes are prevented from finding their way back to the pipe 12.

The attachment may be formed in various ways for convenience in assembling, the preference being that the openings 14 and 15 be positioned in vertical axial alinement, although this may be varied to some extent without departing from the invention, the principal essential of which is that the outlet be located above the inlet for the air in 110

order that the valves may operate by gravity and be of a type which will function with accuracy and freedom of movement.

Having thus described my invention, what

5 I claim as new is:

The combination with an exhaust pipe of an internal combustion engine of a casing connected to the pipe, an outwardly opening valve for the casing controlling the issuance 10 of exhaust gases therefrom, and an inwardly opening valve controlling the admission of air to the casing, said first mentioned valve being adapted to remain open and said second mentioned valve being adapted to re-

main closed during the exhaust stroke of 15 the engine and while the exhaust valve of the engine is open, said first mentioned valve being adapted to close and said second mentioned valve being adapted to open to admit air to the casing and exhaust pipe of the engine immediately subsequent to the closing of the exhaust valve of the engine.

20 In testimony whereof I hereunto affix my signature in presence of two witnesses.

JOHN M. UNDERWOOD.
